UNITED STATES PATENT OFFICE.

JAMES J. JOYCE, OF PORTSMOUTH, NEW HAMPSHIRE.

SAFETY CLASP.

Application filed February 3, 1921. Serial No. 442,132.

To all whom it may concern:

Be it known that I, JAMES J. JOYCE, a citizen of the United States, residing at Portsmouth, in the county of Rockingham 5 and State of New Hampshire, have invented certain new and useful Improvements in Safety Clasps, of which the following is a specification.

This invention relates to a safety clasp for 10 use upon documents, letters, sealed orders, or other important articles, to be conveyed by mail or otherwise, with secrecy.

A further object of the invention is the provision of a safety clasp which is simple 15 in construction, easy of operation, and inexpensive to manufacture.

A further object of the invention is the provision of a safety clasp which will effectively clasp and lock an envelope or the 20 like, in such manner, that the contents thereof cannot be ascertained without destruction to the envelope, or the clasp itself.

Other objects and advantages of the invention will be apparent during the course 25 of the following detailed description.

In the accompanying drawings, forming 30 a part of this specification, and in which like reference characters designate like parts throughout the same:

Figure 1 is a rear elevation of an envelope showing the safety clasp locked thereto.

Figure 2 is a perspective view showing the safety clasp.

Figure 3 is a fragmentary cross sectional 35 view of an envelope showing the safety clasp attached thereto, and in position about to be sealed.

Figure 4 is a fragmentary cross sectional 40 view of an envelope showing the safety clasp attached thereto in sealed position.

Figure 5 is a fragmentary elevation showing the safety clasp locking means.

Figure 6 is a plan view of the safety clasp in its undeveloped position.

Figure 7 is a fragmentary cross sectional 45 view showing the safety clasp in the act of being locked.

Figure 8 is a fragmentary plan view of an 50 end section of the safety clasp showing, a modified form.

In the drawings, wherein for the purpose of illustration is shown a preferred embodiment of my invention, the letter A designates an envelope, having the safety clasp B attached thereto for securely sealing the

envelope to maintain the contents thereof secret.

The safety clasp B comprises the end sections 10 and 11, having one terminal thereof connected by the intermediate section 12. 60 The sections 10, 11 and 12 being preferably stamped from a single piece of material, in position as shown in Figure 6 of the drawings and bent to a substantially Z-formation, upon the dotted lines 13, in substantially the formation shown in Figure 2 of the drawings. The intermediate section 12 is provided with slots 14 and 15 disposed near the ends of the intermediate section 12, at the point of connection with the end 65 sections 11 and 10 respectively.

The free end of the section 10 is provided with a reduced portion 16 having a point 17 upon the end thereof, the section 16 being slightly narrower in width than the slot 14, 70 and adapted for insertion thereto in a manner shown in Figure 3 of the drawings, for maintaining the safety clasp upon an article. The free end of the section 11 is provided with the reduced end 20 having the 75 pointed arrow head 21 thereon; which in reality is formed by the recesses 22, which are stamped in the reduced portion 20 at an angle substantially 45° to the axis of the end section 11, thus forming the barbed ends 23, 80 the purpose of which will be hereinafter more fully disclosed.

For commercial use, the safety clasp is stamped into the substantially Z-shaped 85 formation shown in Figure 2 of the drawings, with the end sections 16 and 20 bent 90 at substantially right angles to their connecting end sections 10 and 11, and pointed in the direction of the intermediate section 12.

In the application of the improved safety clasp to an ordinary envelope, the safety clasp is disposed upon the rear side 25 of the envelope in such manner that the rear side 25 supports the safety clasp B, with the 100 end section 10 depending within the envelope, and intermediate the ends thereof. The first operation is that of pressing upon the front 26 of the envelope and against the face of the end section 10 in such manner, 105 that the reduced pointed end 16 is pushed to pierce the rear face 25 of the envelope, and inserted through the slot 14 in the intermediate section 12. As the end section 10 is pressed toward the intermediate section 110

12, the pointed end 16 will strike the inside face 27 of the end section 11 and be bent upwardly, and securely clamped in the position as shown in Figure 3 of the drawings, 5 for the purpose of maintaining the safety clasp upon the rear side 25 of the envelope A.

In order to seal the flap 30 of the envelope A the same is sealed in the normal manner 10 so that it lies in position with the end section 11 upon the exterior thereof. The arm or section 11 is then pressed toward the intermediate section 12, in such manner, that the arrow head 21 upon the reduced section 15 20 pierces the flap, and projects into the slot 15 in the intermediate section 12, and upon further pressure of the sections together, the point 41 will first strike the apex 31, of the substantially triangular opening 32, in 25 the end section 10 and will be bent downwardly until the entire arrow head 21 is inserted through the widest portion of the triangular opening 32, and the barbed head 23 of the arrow head 21 engages the rear face 35 of the section 10, substantially as shown in Figure 5 of the drawings.

The safety clasp is preferably made of some flexible and durable material and may be of cardboard, celluloid, or some easily 30 bent metal. The safety clasp will be positively maintained in its flat position as shown in Figures 4 and 5 of the drawings, since upon entering, the reduced end 20, and arrow head 21 are bent into parallel alignment 35 with the end section 10 and the rear face 35 thereof. Should there be an attempt to pry the end section 11, which is the only section upon the exterior of the envelope A, such prying will merely have the effect of 40 more securely sealing the barbed end 23 upon the rear face 35 of the section 10, by sliding them upwardly upon the rear face 35 toward the apex 31, of the triangular opening 32 therein.

45 Thus, to open an envelope it will either be necessary to destroy the letter A, or in some manner mutilate the safety clasp B and it can be readily ascertained that the contents of the envelope have been tampered 50 with.

The end 20 may of course be provided with different shaped notches 23' for forming the arrow head 22 and there may be even a plurality of notches as shown in Figure 8 55 of the drawings for more readily adjusting the reduced end 20 to the triangular opening 32.

60 It is to be understood that the form of my invention herewith shown and described is to be taken as the preferred example of the same, and that various changes in the shape, size and arrangement of parts may be resorted to without departing from the spirit 65 of the invention or the scope of the subjoined claims.

I claim:

1. As an article of manufacture, a safety clasp formed of a single strip of flat material, rectangular slots within said substantially flat body, said body having reduced ends thereon adapted for insertion through said slots, said body having a triangular opening therein, and a barbed head upon an end of one of said reduced portions adapted 70 for insertion through said triangular shaped aperture for securely locking the substantially flat body to form a safety clasp.

2. In a safety clasp, the combination, with an article holder having a sealing flap, of a safety clasp comprising a section adapted to be secured to the article holder, and a second section integral with said first mentioned section, and having an arrow headed reduced portion on the end thereof adapted to engage 75 the flap and said first mentioned section for securely sealing the article holder.

3. As an article of manufacture, a safety clasp formed of a length of material bent to provide an intermediate section and a pair of sections bent at opposite ends of the intermediate section and upon opposite sides of the intermediate section, the free end of one of said end sections adapted for engagement with the intermediate section to provide a clasp portion of said end section and the intermediate section, the second end section adapted for engagement at its free end with the intermediate section and the first mentioned end section to provide 90 a second clasp portion of said intermediate section and the second mentioned end section.

4. As an article of manufacture, a safety clasp comprising a pair of end sections, an intermediate section connecting said end sections, and having slots therein narrower in width than the width of said connecting section, one of said end sections having a reduced pointed end thereon adapted to be inserted through a slot in the connecting 105 section for forming a clasp, said section also having a substantially triangular shaped opening therein, the other of said sections having a reduced arrow headed projection on the free end thereof adapted to be inserted 110 through the slot in the connecting section and through the triangular opening in the first mentioned end section for securely locking the sections together to form 115 a safety clasp.

5. As an article of manufacture, a safety clasp formed of a length of material bent to provide an intermediate section and a pair of sections bent at opposite ends of the intermediate section and upon opposite sides 120 of the intermediate section, the free end of one of said end sections adapted for engagement with the intermediate section to provide a clasp portion of said end section and the intermediate section, the second end 125 section adapted for engagement with the intermediate section to provide a clasp portion of said end section and the intermediate section, the second end 130

section adapted for engagement at its free end with the intermediate section and the first mentioned end section to provide a second clasp portion of said intermediate section and the second mentioned end section, the place of connection of the first mentioned end section with the intermediate section being in remote and spaced relation with respect to the connection of the 10 second mentioned end with the intermediate and first named sections.

6. As an article of manufacture, a safety clasp formed of a single length of sheet metal providing an elongated intermediate 15 portion with end portions bent at opposite ends of the intermediate portion on opposite sides thereof, the intermediate portion having substantially rectangular slots transversely at the ends thereof adjacent the connection of the end sections therewith, one of

the end sections having a reduced pointed end adapted for insertion in that slot of the intermediate portion which is remotely positioned with respect to the connection of said end section with the intermediate section to 25 provide a clasp portion, said end having a substantially triangular shaped opening therein adjacent its point of connection with the intermediate section, the second end section having a reduced barbed end adapted for insertion through the other slot of the intermediate section which is positioned remote from connection of the second end section with the intermediate section and to be inserted in the substantially triangular 30 shaped opening of the first mentioned end section to provide a second clasp portion of the second mentioned end section and intermediate section. 35

JAMES J. JOYCE.
